WILLIAM J. SCHULTZ, OF MCKEESPORT, PENNSYLVANIA, ASSIGNOR TO FIRTH STERLING STEEL COMPANY, OF MCKEESPORT, PENNSYLVANIA, A CORPORATION OF PENNSYLVANIA.

ELECTRIC FURNACE.

Application filed September 25, 1925. Serial No. 58,504.

The present invention relates broadly to electric furnaces, and particularly to furnaces of the electrode type.

One of the greatest difficulties encountered in the operation of electric furnaces of the electrode type is the control of the electrode with respect to the bath of metal. It is customary to use motor driven devices, usually cables and cabledrums, to raise and lower the electrodes. Inasmuch as the electrodes require a relatively slight movement, the adjusting motor is usually geared to a cable drum through a worm drive or other low ratio gear. The high speed of the armature is thus transmitted as a slow motion. This speed of the armature, however, presents serious difficulties because of the over travel which it necessarily causes, that is, a motor going at even moderate speed cannot be instantly stopped and any drifting of the motor after the current is cut off represents over travel of the electrodes. Dynamic braking is not always effectual because the retarding current becomes very weak with reduced speed, and a heavy armature and hand wheel represent considerable inertial energy at the lower speeds where dynamic breaking is least efficient.

I propose to obviate the evil effects of the inertia forces of the armature and gearing by providing an electrode controlling mechanism which can be disengaged from the driving motor when the desired electrode travel has been effected. I further provide for engaging the hand wheel which is used for manual operation only when it is desired to adjust the electrodes, so there will be no inertia effect from the hand wheel when the motor is operating.

I further provide stability of the electrodes and insure their absolute control by a construction on the supporting mast which causes the electrodes to always maintain themselves in proper alignment by their own weight.

Furthermore, I secure absolute control of the electrodes by the provision of an improved insulating joint between the electrode holder and its supporting arm, whereby rotation of the electrode holder about the supporting arm is prevented.

In the accompanying drawings, illustrat-

ing the present preferred embodiment of my invention,—

Figure 1 is a side elevation of an electric 55 furnace embodying my invention;

Figure 2 is a top plan view of the furnace shown in Figure 1;

Figure 3 is a rear elevation of the furnace;

Figure 4 is a sectional view on the line 60 IV—IV of Figure 3;

Figure 5 is a sectional view showing the connection between the carbon holder supporting arm and the mast;

Figure 6 is a top plan view of an electrode 65 holder;

Figure 7 is a sectional view of the electrode holder shown in Figure 6;

Figure 8 is a cross section on the line 70 VIII—VIII of Figure 7;

Figure 9 is a diagrammatic view of the gear box used to control the electrode hoist; and

Figure 10 is a wiring diagram of the control system applied to one electrode. 75

In the illustrated embodiment, Figure 1 shows an electric furnace having a body portion 2, a removable top 3 fitted with water-jacketed collars 4 through which protrude the electrodes 5. The electrodes 5 are 80 carried in the electrode holder 6 which are carried by, but insulated from, supporting arms 7. The supporting arms 7 are connected with vertical masts 8 by means of a T-connection 9, as clearly illustrated in Figure 5. The masts 8 are free to move in a vertical direction only, being restrained from any side movement by means of rollers 10, as shown in Figure 4. Vertical adjustment of the masts 8 is accomplished by 85 means of a cable 11 attached at the lower end of the mast to a bracket 12 and carried over a pulley 13 to a hoist drum 14. The hoist drum 14 is controlled by a gear box, as will be hereinafter more fully described. 90

The body portion 2 is fitted with brackets 15 and 16. These brackets are effective for holding the mast guides 17 and for supporting the control platform 18. The control platform 18 is used for mounting all of the 100 mechanism required for controlling the electrodes, since this mechanism must rotate with the furnace body. Suspended from the platform 18 is a driving motor 19 which

is effective for rotating a constant speed driving shaft 20 by means of reducing gears 21 and 22 and a worm and worm wheel 23 and 24.

5 A tilting mechanism is provided whereby the furnace may be rotated on its foundation to effect tapping a heat. This mechanism comprises a motor 25, a gear box 26, a crank 27 and pitman 28, as is well understood in the art.

10 Current is supplied to the electrodes by means of bus bars 29 through flexible cables 30. The bus bars 29 are supported on the electrode holder supporting arms 7 by 15 means of brackets 31 which are insulated from the supporting arms 7 by clamping suitable insulating material between the brackets 31 and arms 7, as is shown in Figure 5. The bus bars 29 terminate on the electrode holder 6 in brackets 32, as shown in 20 Figure 7.

15 The usual method of supporting the electrode holder from its supporting arm involves flanged couplings and bolts, each 25 of which must be insulated. As will be seen from Figures 7 and 8, I provide a much simpler construction. I prefer to make the horizontal supporting arm 7 of heavy tubing. The end of the tubing is crimped to 30 form a series of rounded ridges and depressions, as shown in Figure 8. The electrode holder 6 is formed to cooperate with this construction and bolts 33 are provided for drawing the end of the electrode holder 35 tightly about the supporting arm 7. Insulation is provided by placing some heat resisting insulation 34 about the corrugated portion of the supporting arm and conforming it thereto prior to the application of the 40 clamping end of the electrode holder. The end of the tubing 7 may be insulated from the electrode holder by means of a piece of suitable insulation placed between the electrode holder and the end of the arm, as 45 shown in Figure 7. This type of construction provides a connection which is secure against rotation and free from electrical 50 defects. At the same time, the holder 6 is readily removable if so desired. The arm 7, 55 it will be noted, is prevented from rotation by means of a pin 35 which projects through the T-shaped connection 9 as shown in Figure 5.

55 The electrode holder is provided with the usual water connections 36 and electrode clamping bolts 37, as is usual in such devices.

60 Water for cooling the electrode holder 6 is provided through suitable pipes 39 which lead to hose connections 40. A supply of water for each holder is insured by running a separate pipe thereto. Waste water from the electrode holder 6 is led through hose connections 41 through the guide collars 4 from whence the waste water is led to a 65 common waste pipe 42.

Proper vertical alignment of the mast 8 is at all times secured by means of the construction shown in Figure 4, wherein rollers 10 cooperate with recesses 43. The recesses 43 are cut with increasing curvatures 70 toward the bottom of the recess and are placed on the mast so that the weight of the electrode and its supporting arm and associated parts at all times hold the recess 43 in close contact with the rollers 10, thereby 75 forming a self-aligning construction.

Figure 9 clearly illustrates the mechanism controlling the cable drum 14. The shaft 20 rotating continuously at constant speed, has splined thereon a collar 44 rotating with the shaft and free to move axially thereon. Both sides of the collar 44 are provided with lugs 45 which may cooperate with corresponding lugs 45^a on the internal faces of bevel gears 46 and 47 which are mounted in opposed relationship on the shaft 20 and are free to rotate thereon. The bevel gears 46 and 47 are continuously in mesh with a corresponding bevel gear 48 mounted on a shaft 49 perpendicular to the shaft 20. The shaft 49, by means of a worm 50 and a worm wheel 51, drives a shaft 52 which carries the cable drum 14. As will be evident from the drawings, axial movement of the collar 44 is controlled by a forked 95 arm 53, which in turn may be moved by a hand lever 54 or a cross arm 55. The cross arm 55 may be moved selectively clockwise or anti-clockwise by armatures 56 which are controlled by solenoids 57. It is evident 100 that the bevel gear 48 and, consequently, the cable drum 14, may be rotated in reverse direction by engaging either of the bevel gears 46 or 47 with the collar 44. The drum 14 cannot be operated by tension on 105 the cable 11 because of the friction between the worm 50 and the worm wheel 51. For convenience in mounting, I prefer to place the solenoids 57 below the control platform 110 18, as shown in Figure 1.

110 I provide for manual adjustment of the electrodes by means of a hand wheel 58 mounted on a shaft 59 and controlling a spur gear 60. The spur gear 60 engages a corresponding gear 61 mounted on the shaft 49. The drawing shows the manual control mechanism in position for operating. When the elevation of the electrodes 5 is being controlled by the solenoids 57, all of the hand wheels 58 are moved to place the gear 60 out of engagement with the gear 61, as shown in dotted line position. In this way, I avoid any bad inertia effect from the hand wheel being rotated by the motor. At the same time any of the hand wheels may be pulled out and manual operation afforded on any individual electrode.

115 Figure 10 shows a preferred wiring diagram for the control of one electrode. In this diagram buses 62, 63 and 64 lead to the 120 130

electrodes. Control of the electrode fed by bus 64 is effected by means of current taken from that bus through a transformer 65. The current passing through the secondary of transformer 65 is led through a solenoid 66 and also through a variable resistance 67. The adjustable resistance 67 parallels the solenoid 66, so that the strength of field of the solenoid may be controlled by adjusting the resistance 67. The solenoid 66 controls an armature 68 which acts through a lever 69 to control a contact finger 70. Rapid oscillation of the lever 69 is prevented by means of a dash pot 71. It will be understood that the control mechanism thus far described is of a sensitive nature and operates on a reduced current. To prevent arcing and consequent destruction of the contact finger 70, a step-down transformer 72 is provided. This transformer takes the current from a suitable source 73 and supplies what current is necessary to operate the relays 74 and 75. These relays are controlled selectively through contacts 76 and 77 by means of the contact finger 70. The heavier current required to operate the solenoids 57 is taken from the source 73 and controlled selectively by the relays 74 and 75.

It will be understood that the whole control mechanism will operate satisfactorily on alternating current. This is an important feature. Heretofore, it has been customary to operate the electrodes on alternating current and the control mechanism on direct current. Because of this it was necessary to have a no-voltage release, that is, a control whereby the direct current was shut off in case the alternating current failed. This was true because the effect of a reduced current through the busses 62, 63 and 64 is to cause the control mechanism to lower the electrode, and in the event that the alternating current failed the direct current control system caused the electrode to plunge into the bath. With my improved control system a failure of the alternating current causes the whole mechanism to remain at a standstill, because the same source is used for the electrodes and for their control.

It will be obvious that the gear box might be replaced with cone friction wheels, and the jaw clutch formed by the lugs 45 and 45^a replaced by friction disk clutches without departing from the spirit of the invention.

The advantages of the present invention arise from the provision of a construction wherein the electrodes in an electric furnace may be maintained in proper alignment, electrically insulated from the structure and secured against sidewise movement.

Further advantages arise from the provision of a means whereby the adjustment

of the carbon is made accurate and free from the inertia effect of the rotating armature of the driving motor, whereby drifting and over travel is avoided.

Still greater accuracy and ease of adjustment is provided in a hand operating mechanism wherein the hand wheel is engaged with the hoist mechanism only when it is desired to operate the electrodes manually. In this way I avoid the inertia effect of the spinning hand wheel when the hoist is motor operated.

While I have described the present preferred embodiment of my invention, it will be understood that changes may be made in the construction disclosed therein and method of working the same without departing either from the spirit of the invention or the scope of the following claims.

I claim as my invention:

1. The combination with an electric furnace having an adjustable electrode, of means for advancing or retracting the electrode including a motor, an electrode-moving element driven thereby, and a reversing clutch interposed between the motor and the electrode-moving element.

2. The combination with an electric furnace having an adjustable electrode, of means for advancing or retracting the electrode including a continuously driven motor, an electrode-moving element driven thereby, a reversing clutch interposed between the motor and the electrode-moving element, and manually operable electrode adjusting means movable into and out of driving connection with said electrode-moving element.

3. The combination with an electric furnace having an adjustable electrode, of means for advancing or retracting the electrode including a continuously operating motor, an electrode-moving element driven thereby, a reversing clutch interposed between the motor and the electrode-moving element, and electro-magnetic means for operating the clutch.

4. The combination with an electric furnace having an adjustable electrode, of means for advancing or retracting the electrode including a continuously operating motor, an electrode-moving element driven thereby, a reversing clutch interposed between the motor and the electrode-moving element, electro-magnetic means for operating the clutch, and means controlled by a character of the electrode circuit for controlling said electro-magnetic means.

5. The combination with an electric furnace having an adjustable electrode, of means for advancing or retracting the electrode including a continuously operating motor, an electrode-moving element driven thereby, a reversing clutch interposed between the motor and the electrode-moving element, electro-magnetic means for operat-

ing the clutch, means controlled by a character of the electrode circuit for controlling said electro-magnetic means, and electro-magnetic means responsive to current variations in the electrode circuit for controlling the operation of said clutch.

6. The combination with an electric furnace having an adjustable electrode, of a drum, a flexible connection between the drum and the electrode, a motor for driving the drum, a reversing clutch between the motor and the drum, and a control for the clutch.

7. The combination with an electric furnace having an electrode movement by gravity in one direction, of a drum, a cable connecting the drum and the electrode for raising and lowering the electrode, a worm gear through which the drum is operated, a continuously operable motor for driving the worm, and a reversing clutch interposed between the motor and the worm gear.

8. The combination with an electric furnace having an electrode movement by gravity in one direction, of a drum, a cable connecting the drum and the electrode for raising and lowering the electrode, a worm gear through which the drum is operated, a continuously operable motor for driving the worm, a reversing clutch interposed between the motor and the worm gear, and an electro-magnetic control for the clutch.

9. The combination with an electric furnace having an electrode movement by gravity in one direction, of a drum, a cable connecting the drum and the electrode for raising and lowering the electrode, a worm gear through which the drum is operated, a continuously operable motor for driving the worm, a reversing clutch interposed between the motor and the worm gear, and a hand operated mechanism between the worm and clutch for effecting a movement of the worm, said hand operated mechanism being movable into and out of driving connection with the worm, whereby the worm may be operated through the clutch without operation of the hand operated mechanism.

50 10. The combination with an electric furnace having a plurality of electrodes, of means for adjusting the electrodes including a continuously driven shaft, a separate electrode moving element for each electrode, a reversing clutch between the shaft and each electrode moving element and an independent control for each reversing clutch.

11. The combination with an electric furnace having a plurality of electrodes, of means for adjusting the electrodes including a continuously driven shaft, a separate electrode moving element for each electrode, a reversing clutch between the shaft and each electrode moving element, an independent control for each reversing clutch, and an

electro-magnetic means for controlling the operation of each reversing clutch.

12. The combination with an electric furnace having a plurality of electrodes, of a cable and drum for each electrode for effecting the movement thereof, a common driving shaft for transmitting power to each drum, and a reversing clutch interposed between the driving shaft and each drum.

13. The combination with an electric furnace having a plurality of vertically movable electrodes, of a cable and drum for adjustably moving each electrode, a worm gear through which each cable and drum is operated, a common shaft for transmitting motion to each worm gear, and a reversing clutch interposed between the shaft and each worm gear.

14. The combination with an electric furnace having at least one electrode, of means for raising and lowering the electrode comprising a continuously rotating driving element, a driven element connected to the electrode, and means for transmitting motion in reverse directions from the driving means to the driven means.

15. The combination with an electric furnace having at least one electrode, of means for raising and lowering the electrode comprising a continuously rotating driving element, a driven element connected to the electrode, means for transmitting motion in reverse directions from the driving means to the driven means, and an electro-magnetic control for said last named means.

16. The combination with an electric furnace having a plurality of electrodes, of means for raising and lowering the several electrodes comprising a continuously rotating driving element, a plurality of driven elements connected to the respective electrodes, and a plurality of means for transmitting motion in reverse directions from the driving element to the driven elements.

17. The combination with an electric furnace of an electrode, and control means for the electrode including a laterally projecting arm on which the electrode is carried, a longitudinally movable grooved mast to which the arm is rigidly secured, and guide rollers whereby the mast is maintained in a predetermined path, said guide rollers being shaped to cooperate with the grooved mast and prevent rotational movement thereof.

18. The combination with an electric furnace of an electrode, and control means for the electrode including a laterally projecting arm on which the electrode is carried, a longitudinally movable mast to which the arm is rigidly secured, longitudinal grooves on said mast, said grooves being formed with increasing curvature toward the deepest portion thereof, and guide rollers cooperating with the grooves in the mast, said

guide rollers being shaped with transversely curved surfaces which engage the grooves in the mast, thereby maintaining the mast against lateral displacement and preventing 5 rotational movement of the same.

19. An electric furnace comprising a furnace structure having a plurality of opposed rollers therein, a longitudinally movable mast guided by said rollers, a laterally projecting arm secured to the mast and having its outer projecting end of non-circular cross-section, a layer of heat resisting insulation conforming with the projecting end, and an electrode holder at the end of the arm 10 secured thereto by a clamping portion of the holder cooperating with the arm portion of non-circular section.

20. An electric furnace comprising a furnace structure having opposed guide rollers 20 therein, a longitudinally movable mast having grooves therein for co-operative engagement with the rollers, a laterally projecting tubular arm secured to the mast and having its outer projecting end fluted, a layer of 25 heat resisting insulation conforming with the fluted end portion of the arm, an electrode holder at the end of the arm secured thereto by a clamping portion of the holder 30 cooperating with the fluted portion of the arm.

21. The combination with an electric furnace of an electrode, a source of alternating current connected to the electrode, means for advancing and retracting the electrode controlled by a character of the electrode circuit 35 and operated by an alternating current inductively derived from the same source supplying the electrode.

22. An electric furnace comprising a furnace structure having a guide-way therein, 40 opposed rollers in the guide-way, a mast in the guide-way having grooves therein for cooperative engagement with the rollers, a rigid tubular arm having a fluted outer end portion secured to the mast and projecting 45 laterally therefrom, an electrode holder at the end of the arm insulated therefrom and secured thereto by a clamping portion of the holder cooperating with the fluted end portion of the arm, an electrode in the 50 holder, means for raising and lowering the mast, said means including a drum, a cable connecting the mast and the drum, a continuously rotating driving motor, and means for intermittently transmitting motion in 55 reverse directions from the driving motor to the drum.

In testimony whereof I have hereunto set my hand.

WILLIAM J. SCHULTZ.
